UNITED STATES PATENT OFFICE

2,442,028

COMB

Lewis S. Utley, Forest Hills, N. Y., assignor to
 Columbia Protektosite Company, Inc., Carlstadt, N. J., a corporation of New Jersey

Application September 19, 1945, Serial No. 617,247

3 Claims. (Cl. 132—11)

1

This invention relates to combs.

One object of the invention is to provide a comb having improved means for supporting the same.

According to the usual custom, a comb is placed to rest on a side in which position it occupies considerable space on a lady's dresser or vanity. In a pullman sleeper, in which space is especially limited, the comb is even more in the way, and the result is that oftentimes other articles overlap on and conceal the comb. While many combs are made of pocket size, the demand for the large size comb is strong and hence the need for avoiding these and still other difficulties. Among the latter, it may be mentioned that when a comb is washed and dried, water generally remains between the teeth, and I have perceived that evaporation proceeds very slowly when the comb is lying in its usual position but proceeds more rapidly when the comb is, for instance, suspended.

It is therefore an object of the invention to provide improved means for supporting a comb on a plane surface with its teeth in upwardly projecting position.

Because it is the practice to mold combs with the parting line of the mold along the central plane of the comb, a small burr is generally raised which is not particularly noticeable along the edges of the comb, but which would interfere with the seating of the comb in vertical position on a plane surface.

It is therefore another object of the invention to furnish an improved comb with a base which does not require laborious removal of the parting line burr.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Fig. 1 is a fragmentary diagrammatic elevation showing a comb embodying the invention.

Fig. 2 is a view in end elevation thereof.

Fig. 3 is a transverse sectional view of the comb.

The advantages of the invention as here outlined are best realized when all of its features and instrumentalities are combined but, useful em-

2

bodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a comb embodying the invention. The same may include a row of comb teeth 11 which may be large or small, coarse or fine, and straight or wavy. These teeth are mounted on a back 12 which is usually slightly thicker than the teeth. 15 Heretofore this base had its outer marginal surface curved in greater or less degree. Because combs molded of plastic are formed with the parting line of the mold in the central plane of the comb, a minute longitudinal burr such as 10a occurs along the edges of the comb. Hence in well designed combs the curvature of the outer surface of the base is reduced almost to the degree of providing a conical surface so that this burr along the apex of that surface is less pronounced and does not appear as an interruption in a curved surface.

For supporting the comb so that it may rest on a plane surface 13 with the row of teeth upright, I provide a base 14 which is preferably 20 molded as an integral part of the comb. This base has a width substantially greater than the thickness of the back. For example while the back may be about 0.2 inch thick, that of the base may be about 0.5 inch thick to afford a 25 stable support for the comb. Furthermore the base 14 is sufficiently removed from the teeth to avoid obstruction in the use of the comb. Thus the base begins at a point at least 0.5 inch away from the root of the teeth. The center of gravity 30 of the comb will be below its geometric center line, the base 14 exercising a stabilizing influence on the comb. By the construction shown, the comb may be used at the usual small acute angle to a person's head in combing the hair, and the 35 base 14 affords a good grip in manipulating the comb.

Formed in the bottom of the base 14 is a longitudinal groove or recess 15 thereby assuring a 40 better seating on the surface 13 and causing the burr to be elevated above that surface so that the base forms a plane seat. Hence removal of the burr in the groove 15 is not required, and the 45 grinding and polishing operations that would be entailed are avoided. By making the groove relatively large, the amount of plastic used is re-

duced and the weight of the comb is not materially increased.

The invention is thus well embodied in a one-piece, molded plastic comb of homogenous material throughout, adapted for inexpensive manufacture, and being neat, durable, reliable and efficient in realizing the objects of the invention.

I claim:

1. As a new article of manufacture, a hair comb having a body comprising a single, straight row of comb teeth and a coplanar, relatively thin back, and a base integrally formed to extend along said body so that the back interconnects with and lies between the comb teeth and the base, said back having a width sufficient to permit finger gripping therat in handling the comb, the base being characterized by a bottom seating surface adapted for the support of the comb in a horizontal plane in stand-up position with the comb teeth projecting upwardly, said bottom seating surface lying in a plane approximately at right angles to an axis of said body and being substantially equally extended on opposite sides of said axis of the plane of the body to provide a width at the seating surface substantially the width of the base to constitute a support for maintaining the comb in the stand-up position, the comb including the teeth, back and base being of one-piece construction and consisting throughout of a homogeneous material the major portion of whose mass is in the region at the lower part of the comb.

2. As a new toilet article of manufacture, a one-piece stand-up comb of homogeneous material molded with integral portions comprising an elongated back, a single row of teeth having root portions extending from one longitudinal edge of said back and having axes of said back and teeth projecting in the same plane, said back being relatively thicker than the teeth, and a base extension formed on the edge of said back

opposite said teeth root portions, said base extension terminating in a seating surface extending in a plane perpendicular to said first mentioned plane and having a width at least equal to said width of the back, said base extension being substantially wider than the thickness of said back to provide therewith efficient finger gripping means to facilitate manipulation of the comb and so constructed and arranged to constitute said seating surface as a support in a horizontal plane for maintaining the comb in a freely resting stand-up position with the teeth projecting upwardly when the comb is not in use.

3. As a toilet article of manufacture, a stand-up comb molded of integral portions comprising an elongated back formed with a base having a relatively wide edge surface, said base interconnecting with a single row of uniformly spaced comb teeth extending from a side thereof opposite said surface, said back being of gradually increasing thickness from said side to the edge surface and having a width therebetween of at least one-half inch, the width of said base surface being at least equal to the width of said back and at least twice the thickness of said back at said base side for providing sufficient finger grip means therat to manipulate the comb and to support same on said base edge surface resting in a horizontal plane with the teeth in an upright position.
